UNITED STATES PATENT OFFICE.

JULES SARRAZIN, OF NEW ORLEANS, LOUISIANA.

AUTOMATIC MOSQUITO-BAR FRAME.

SPECIFICATION forming part of Letters Patent No. 435,191, dated August 26, 1890.

Application filed November 16, 1889. Serial No. 330,670. (No model.)

To all whom it may concern:

Be it known that I, JULES SARRAZIN, a citizen of the United States, residing at New Orleans, in the parish of Orleans and State of Louisiana, have invented certain new and useful Improvements in an Automatic Mosquito-Bar Frame; and I do declare the following to be a full, clear, and exact description of the invention, such as will enable others skilled in the art to which it appertains to make and use the same.

My invention relates to an improvement in an automatic mosquito-bar frame, in which the draw-bar is made to operate in conjunction with the side bars by means of rollers, also by means of cords with weights attached.

The objects of my improvements are to provide a device that will enable a mosquito-net to be drawn over the bed in a noiseless manner, and when the mosquito-net is loosened at the foot and side of the bed to be drawn back automatically. I attain these objects by the mechanism illustrated in the accompanying drawings, in which—

Figure 1 is a side elevational view. Fig. 2 is a perspective top view showing the metal frame with mosquito-net drawn.

Similar letters refer to similar parts throughout both views.

In constructing my invention I use an ordinary metal draw-bar, as shown by E, upon the ends of which I place an attachment, as shown by F, and within the opening in this attachment F, I insert the side bars D.

G are metal hooks which hold side bars D in position.

H are metal rings attached to the mosquito-net, and which rest on the side bars.

J is a cord and tassel attached to draw-bar E for drawing the mosquito-net over the bed.

M is the canopy of the bed, to which pulleys L are attached.

K are cords attached to draw-bar E, and which pass over pulleys L.

N are weights or sand-bags attached to cords K, and which permit mosquito-net A to be drawn back when the front portion of the mosquito-net, as shown by C, is released. The weights N do not exceed eight ounces each,

and these are preferably made of sand in order to render the movement of the weights

and mosquito-net noiseless. The attachments F, having rollers which are made of a plastic material, also prevent all noise as they travel back and forth over side bars D.

55

B shows the top of the mosquito-net.

The construction shown is an improvement upon my application filed on September 9, 1889, for devices for mosquito-bar frames, as I do not wish to claim the particular form and 60 construction of the attachment F, as it is shown, described, and claimed in said former application.

The mode of operation is as follows: The mosquito-net by means of cord J, attached to draw-bar E, is drawn over the bed, as shown in Fig. 1. The front portion of the mosquito-net, as designated by C, is pushed under the mattress. This holds the mosquito-net in position when drawn over the bed. When it is 70 desired to draw back the mosquito-net, it is released at the side of the bed and in front, and the weights N, descending, will draw back the net in a noiseless manner.

Having fully described my invention, what I 75 claim, and desire to secure by Letters Patent, is—

The combination, with a bed-frame, of the horizontal frame M, secured to the head-board of the bed and supported on brackets, as 80 shown, the horizontal side bars or rods supported in said frame by depending screw-eyes, and the pulleys L, depending from the rear under side of the frame, the sliding cross bar or rod E, having the attachments F on its opposite ends, and said attachments carrying rollers to travel on the side rods, the ropes K, connected at their forward ends to the transverse slide-bar and passing through the pulleys and carrying weights N at their opposite 90 ends, whereby the canopy may fold back automatically, and the cords J, also secured to the transverse slide-bar for retaining the canopy in an open position, substantially as specified.

95

In testimony whereof I affix my signature in presence of two witnesses.

JULES SARRAZIN.
